UNITED STATES PATENT OFFICE.

ARTHUR L. STANFORD, OF CHICAGO, ILLINOIS.

DRAFT-GEAR.

No. 927,382.

Specification of Letters Patent. Patented July 6, 1909.

Application filed June 1, 1908. Serial No. 436,003.

To all whom it may concern:

Be it known that I, ARTHUR L. STANFORD, a citizen of the United States, residing at Chicago, in the county of Cook and State of Illinois, have invented certain new and useful Improvements in Draft-Gears, of which the following is a specification.

As frequently constructed, draft gears for use on railway cars embody wedge blocks and wedges, which are intended to secure the necessary frictional action by a wedging movement of the parts, either in combination with suitable spring mechanism or without the employment of such mechanism. Under the onerous conditions of actual usage, it frequently happens that the great pressure to which the wedges are subjected causes them to bind or lock so tightly together that they will not release when relieved from pressure, so that the gearing will be thrown out of commission as a means for relieving the cars from shocks or jolts. Furthermore, the wedge mechanism of this character ordinarily changes the direction of the line of pressure and concentrates the pressure against the walls of the casing in such manner as to subject them to a bursting strain, which the casing must be heavily reinforced to withstand.

The object of the present invention is to overcome the objections above noted and to provide a frictional action of great intensity without changing the direction of the line of pressure and without subjecting the walls of the casing to frictional action or lateral strain.

A further object of the invention is, to maintain the line of pressure centrally between the walls of the casing and to evenly distribute the pressure through the walls and the end of the casing without subjecting the casing to a direct frictional action which would tend to wear out the casing and necessitate its removal.

The invention contemplates the use of frictional members which can be readily removed from the casing and renewed from time to time without disarranging or impairing the more permanent portions of the mechanism.

The invention also contemplates the use of springs which act in conjunction with the frictional members and which are so arranged that they will be protected against excessive compression.

The invention further is intended to se-

cure a compactness of arrangement which will permit a draft mechanism of high efficiency to be readily mounted within draft rigging of standard construction.

The invention further contemplates an arrangement which will entirely eliminate all wedging action so that the compression and release of the frictional members will be performed smoothly and evenly despite the high degree of friction secured by the gearing.

Further objects of the invention will appear from a detailed description of the invention, which consists in the features of construction and combination of parts herein-after described and claimed.

In the drawings, Figure 1 is a side elevation of the draft gearing of the present invention as applied to a draw bar and coupling head of standard construction; Fig. 2 a sectional plan view of the gearing, taken through the center thereof and showing the gearing in uncompressed condition; Fig. 3 a similar view, showing the gearing subjected to a maximum compression; Fig. 4 a longitudinal sectional elevation, taken through the center of the gearing; Fig. 5 a cross sectional view, taken on line 5—5 of Fig. 4; Fig. 6 a cross sectional view of the casing, looking toward the rear end thereof; and Fig. 7 a perspective view of the frictional members of the gearing.

The gearing comprises a substantially rectangular casing having side walls 8 and 9, a floor 10 and a top 11. The casing further comprises a rear end wall 12 which is projected beyond the top walls of the casing to provide side flanges 13, a top flange 14 and a bottom flange 15, the top and bottom flanges being narrower than the side flanges shown in Fig. 6. The side walls of the casing are reinforced by means of longitudinally extending ribs 16 which are flared at their rear ends 17 at the point where the ribs merge into the side flanges at the rear end of the casing. Intermediate the ribs 16 the side walls of the casing are further reinforced by a short tapered web 18 which lies within the corner or angle between the end of the side wall and flange. The top and bottom walls of the casing are reinforced by means of longitudinally extending ribs 10 which afford a bearing for a draft yoke 20 of standard size and construction, the faces of which yoke rest upon the ribs 19, which ribs are rounded at their rear ends 21 at the point where they

merge into the top and bottom flanges 14 and 15, respectively. The reinforced end wall of the casing finds a bearing against suitable stops or shoulders 22 which are secured to the car sills 23 in the usual manner.

The forward end of the casing is open and has entered thereinto an outer socket plate 24 which is provided, on its outer face, with an outwardly projecting stop 25 of tubular formation, which stop is encircled by a heavy spring 26. The outer coil of the spring is cut down or tapered to provide a flat bearing surface for a follower plate 27 which bears against an enlarged inner head 28 of a draft bar 29 having a coupler head 30 of standard formation at its outer end. The yoke, draft bar and coupler head are of standard construction and need not be described in detail.

The rear or closed end of the casing receives an outer coiled spring 31 which encircles an inner coiled spring 32, the rear coil of which latter spring surrounds a circular boss 33 formed on the end wall of the casing. The forward ends of both the inner and outer springs bear against an inner socket plate 34, which corresponds in arrangement and function to the outer socket plate 24. The inner socket plate is provided, on its rear face, with a boss 35 in alignment with the boss 33, which bosses serve to hold the inner coiled spring and properly center it with respect to the outer coiled spring. Each of the socket plates is provided with a recess 36, into which recesses are entered friction members which act in opposition to one another.

The friction members are in the form of shoes 37 and 38, each of which is in the form of a block having a flat outer face 39 which fits snugly within the recesses provided therefor. Each of the shoes is provided with a concave inner face 40 which is struck on the arc of a circle, having a diameter slightly greater than the distance between the centers of the two faces. It is intended to form the shoes of rough cast metal so that the maximum friction will be afforded by their concave bearing faces. The friction shoes coöperate with an inner friction disk 41 and a pair of outer friction disks 42. The friction disks lie in facial contact with one another, and the inner disk, in the preferred construction, is of twice the thickness of each of the outer disks and occupies a position between the two. Each of the disks is of cylindrical formation, being curved on a circle having the distance between the center points of the operating friction shoes as a diameter. The inner friction disk is slightly off center transversely with respect to the two outer friction disks, so that the disks overlap one another to a slight extent. In view of the fact that the line of curvature of the disks is struck on a radius slightly shorter than the radius of the concave bearing faces of the shoes, it will be apparent that the disks will

contact the curved surfaces of the shoes on but one side and that a slight clearance will be afforded on the other side.

The inner friction disk is provided, on one side, with an outwardly projecting rounded pivotal arm 43 which projects through an opening 44 in the adjacent side wall of the casing intermediate the side ribs 16 and is cored out to provide a pivotal bore 45 which receives a heavy round pivot pin 46, the ends of which are entered through protuberant bosses 47 formed on the side of the casing above and below the opening 44. The two outer friction disks 42, in like manner, are each provided, on one side, with a pivotal arm 48, which arms are entered through slots or openings 49 in the side wall of the casing, which, at this point, is thickened to provide a protuberant boss 50 which receives a heavy pivot pin 51 entered through a cored hole 52 in the protuberant boss and through cored holes 53 in the projecting arms. The pivot pins on both sides are preferably in the form of rough castings which are entered through rough pivotal holes in the projecting pivotal arms, whereby the frictional action between the surface of the pins and the pivotal arms will be maintained at a maximum.

Referring to Fig. 2, it will be noted that when the parts are in normal or uncom-pressed condition the friction disks will occupy a position slightly forward of the center line between the two pivotal points, and that the several friction disks will contact the concavely curved acting faces of the shoes only on the side adjacent the pivotal mounting for the disk, a clearance being afforded between the opposite surface of the disk and the adjacent wall of the shoe. When the parts are moved to full compressed position, as shown in Fig. 3, the centers of the friction disks will have been swung to a position to the rear of the center line between the two pivotal points equal in extent to the distance in advance of such line previously occupied by the disks. The parts are so proportioned that the disks will swing in the arcs of circles which intercept each other twice during the complete retraction of the disks, which swing of the disks results in a turning or sliding movement with respect to the surfaces of the coöperating shoes, whereby a high degree of friction will be generated. When the disks have been swung to an intermediate position, in which their centers are coincident with the line between the two axes of movement, the respective disks will contact the concave surfaces of the bearing shoes only on the side non-adjacent the axial center. It will thus appear that during the complete movement of the disks from initial to final position they will move from contact with one side of the concave surfaces over to the other side and then back to the initial points of contact. The intention is to provide a

concavity in each of the shoes just sufficient to permit of this shifting movement of the disks while maintaining a close frictional contact between the disks and the shoes at the intended points. The rough end of the castings serves to maintain a very considerable degree of contact between the surfaces of the shoes and the surfaces of the disks at all points in their line of travel.

- 10 In order to maintain the pivot pins against rotation so that friction may be generated between the pins and the pivotal arms of the disks rather than between the pins and the casing, keys 54 and 55 are inserted within co-
15 operating keyways 56 and 57 in the pins and in the walls of the bosses, respectively, the walls of the bosses, at a point 58, adjacent the inserted key, being suitably thickened to compensate for the provision of the keyway.
20 As shown in Fig. 5, the pin which pivots the intermediate disk is held by two keys which occupy positions near the ends of the pin, whereas the pin which pivots the two outer disks is held against rotation by a single key
25 which occupies a position near the center of the pin, being entered into place through an extended keyway.

In use, slight shocks or jars will be taken up by the forward spring 26, without bringing the frictional members into play and without appreciably compressing the rear springs. In case of heavier shocks or jars, the forward spring can be compressed until the follower plate 27 is brought into contact
35 with the forwardly extending stop 25, which prevents further compression of the forward spring, which spring is constructed to maintain a slight clearance between the coils even when compressed to its fullest extent, as
40 shown in Fig. 3. A continued thrust of the follower plate simultaneously sets up a frictional action and a spring action, causing the forward friction shoe to bear against the friction disks and move them rearwardly from
45 their initial position. Such movement is likewise imparted to the rear springs, so that the continued movement due to the heavy shock or jar will set up a powerful frictional and spring action, which increases very rapidly as the parts are moved farther and farther out of normal position. The frictional action, due to a swinging movement of the disks under the direct thrust of the forward friction shoe, will be set up, in part, at the points of contact
55 between the disks and the forward and rear shoes, and, in part, against the inner sides of the pivot pins, against which the disks are thrust when subjected to pressure. The pressure, due to the direct thrust of the forward friction shoe, will be transmitted through the disks, the rear shoe and the springs against the rear end wall of the casing; and the pressure transmitted to the pivotal pins will be distributed throughout the reinforced side walls of the casing, so that no por-

tion of the casing will be subjected to a bursting strain or excessive pressure.

The formation of the frictional members is one which enables the parts to be very compactly arranged, in view of the fact that 70 convex and concave surfaces are fitted one into the other; and the nature of the device is one which enables the frictional members to be readily renewed, after excessive wear, without impairing in any way the more permanent portions of the draft gearing. The inner or rear springs are protected by the forward end of the casing, which is intended to receive the contact of the follower plate when the springs have been subjected to 80 their ultimate degree of compression, the springs being constructed to provide a slight clearance between the coils, even when so compressed.

The structure is substantially symmetrical 85 with respect to its longitudinal center, so that the strain will be equally distributed to both sides of the casing, and the absence of wedging surfaces eliminates the possibility of any locking or cramping of the parts. 90

Although the invention has been described with considerable particularity as to detail, it is plain that the number and arrangement of the friction members can be considerably changed without departing from the spirit of 95 the invention.

In the case of draft gearing embodying wedging frictional members, difficulty is experienced in returning the gearing to normal position, and spring action is relied upon to 100 secure such return. In the present invention, the frictional members will return instantly to normal position, when subjected to even a slight pressure, and wearing, due to frictional action on the release, will be entirely eliminated. 105

What I regard as new and desire to secure by Letters Patent is:

1. In a draft gearing, the combination of a casing, an intermediate friction disk and two outer friction disks, the intermediate disk being of substantially twice the thickness of each of the outer disks, said disks having rounded frictional surfaces, pivotal arms outwardly projecting from the disks, pivot pins 110 entered through said pivotal arms and through the side walls of the casing for pivoting the disks normally off center with respect to one another, forward and rear friction shoes having concave acting faces bearing against the surfaces of all the disks, a rear spring adapted to hold the rear shoe in engagement with the disks, and a member bearing against the forward shoe and forwardly projecting beyond the casing and adapted to 115 impart a compressing action to the forward shoe, substantially as described. 120

2. In a draft gearing, the combination of a casing, an intermediate friction disk and two outer friction disks, the intermediate disk be- 130

ing of substantially twice the thickness of each of the outer disks, said disks having rounded frictional surfaces, pivotal arms outwardly projecting from the disks, pivot pins entered through said pivotal arms and through the side walls of the casing for pivoting the disks normally off center with respect to one another, forward and rear friction shoes having concave acting faces bearing against the surfaces of all the disks, a rear socket plate carrying the rear friction shoe, inner and outer rear springs bearing against said socket plate, a forward socket plate carrying the forward shoe and provided with a forwardly extending stop member normally projecting beyond the casing, and a forward spring surrounding said stop member and normally projecting beyond said member for compensating slight shocks or jars, substantially as described.

3. In a draft gearing, the combination of a casing, an intermediate friction disk and two outer friction disks, the intermediate disk being of substantially twice the thickness of each of the outer disks, said disks having rounded frictional surfaces, pivotal arms outwardly projecting from the disks, pivot pins entered through said pivotal arms and through the side walls of the casing for pivoting the disks, forward and rear friction shoes

having concave acting faces bearing against the surfaces of all the disks, and means for holding the friction shoes in frictional engagement with the disks, substantially as described.

4. In a draft gearing, the combination of a casing, two friction members overlying one another and pivoted to opposite sides of the casing and having rounded friction surfaces, forward and rear friction shoes having concave acting faces bearing against the rounded faces of the disks, and means for holding the friction shoes in frictional contact with the disks, substantially as described.

5. In a draft gearing, the combination of a casing, two flat friction members overlying one another and having rounded frictional surfaces, each of said members having an outwardly projecting pivotal arm, pivot pins on opposite sides of the casing entered through said arms and through the casing, forward and rear friction shoes having concave acting faces bearing against the rounded faces of the disks, and means for holding the shoes in frictional contact with the disks, substantially as described.
